TRANSFORMER

Charles Philippe Boucher, Paterson, N. J., assignor to Boucher Inventions, Ltd., Washington, D. C., a corporation of Delaware

Application June 13, 1940, Serial No. 340,391

11 Claims. (Cl. 171—119)

This invention relates to electrical transformer apparatus and more particularly to transformer apparatus suitable for the operation of negative loads such as luminous gas discharge tubes.

One of the objects of my invention is to provide simple, compact and thoroughly reliable transformer apparatus which is well adapted to withstand the many varying conditions of load and whole or partial short-circuit encountered in actual practical use.

Another object is the provision of power transformer apparatus which is highly efficient and particularly economical in construction, installation, and operation, enjoying low copper and iron losses, a high rate of heat dissipation and good operating power factor.

A further object of my invention is to provide a transformer of symmetrical construction which is balanced in operation and which provides individual protection for each coil section of the secondary winding in the event of short circuiting of that coil section or its load.

Other objects will be in part obvious and in part pointed out hereinafter.

The invention accordingly consists in the combination of elements, features of construction and arrangement of parts, and in the several steps and the relation of each of the same to one or more of the others as described herein, the scope of the application of which is indicated in the following claims.

In the accompanying drawings, Figure 1 is a diagrammatic representation of my transformer apparatus in single form, and

Figure 2 is a diagrammatic representation of a modified form of my transformer apparatus in double form.

As conducive to a clearer understanding of certain features of my invention it may be noted at this point that in the operation of a luminescent sign or display employing one or more luminescent tubes of desired size and configuration high potential electrical energy is required. Ordinarily the desired high potential electrical energy is supplied by alternating current transformer apparatus connected to a standard single phase sixty cycle source at either one hundred and ten volts or two hundred and twenty volts. The secondary windings of these transformers are connected directly to their loads by way of high tension cables attached to high tension bushings. These high tension cables and bushings are required because the voltage difference between the ground and each side of the circuit reaches high values during certain instants of

operation. In certain heretofore known and/or used transformer systems, the plurality of tubes necessary for operation of a single sign or display have been energized by way of a corresponding plurality of transformers in order that the energizing potential may not reach values in excess of those specified by the Fire Underwriters. The cost of equipment for such a system is excessively high and also the labor cost is high since a separate rate charge is made for the installation of each unit. In some heretofore known and/or used transformers these objections have been alleviated somewhat by providing a transformer having two secondary winding coil sections connected in series with the midpoint of the winding grounded. In even the moderately large luminescent signs several of these transformers are required in order to energize the complete display.

One of the outstanding objects of my invention is the provision of transformer apparatus which further alleviates these difficulties, giving a single, compact, inexpensive unit requiring but a single connection to the source of supply and yet giving efficient and thoroughly reliable operation of a plurality of luminescent tubes of a display or sign.

It may be further noted that in the actual operation of a luminescent tube system the tubes frequently become grounded between electrodes by moisture, insect bodies, or other conditions, or the coil sections may themselves become grounded. In the usual transformer employing economical fine-wire secondary coil sections, the short-circuiting of a coil permits the flow of an excessive current until the coil becomes burned out. The only way to avoid this result is by increasing the size of the copper wire of the secondary coil sections until it is large enough to carry the short-circuit current. Such an expedient materially increases the cost of the transformers.

In the construction of transformers it is customary to form the core parts of many laminations bound together to form a compact mass, this construction serving to materially reduce eddy current losses. The laminations are held together and the separate core parts are also united by means of rivets or bolts in transformers as they are now constructed. The presence of the rivets or bolts counteracts to some extent the advantages of a laminated core because they promote the formation of eddy currents, with a consequent reduction in efficiency.

An important item of cost in the construction of transformer cores is the expense involved in providing the dies used in stamping laminations

of various forms. In certain heretofore known and/or used transformers, core parts of several different sizes and configurations are used. Such a construction is expensive because a separate die is required for each part of a different shape.

Referring now more particularly to the practice of my invention, attention is directed to Figure 1 of the drawings wherein, illustratively, a luminescent gas filled tube T is supplied with high potential alternating-current electrical energy from transformer apparatus generally indicated at 10, which in turn is energized in a manner more particularly described hereinafter.

The transformer 10 comprises a core, a primary winding, and a secondary winding mounted on the core. The core includes two parallel linear members 11 and 12 between which are interposed the substantially C-shaped members 13 and 14. The primary winding P is mounted on the linear member 11 in the space between the C-shaped members 13 and 14. Two coil sections S₁ and S₂, forming the secondary winding, are mounted respectively on the long legs 13a and 14a of the C-shaped members 13 and 14. The long leg 13a abuts the member 11 at its left end and the member 12 intermediate its ends but near the left end thereof. Likewise the long leg 14a abuts the member 11 at its right end and the member 12 intermediate its ends but near the right end. In order to prevent relative longitudinal motion of the parts without requiring additional holding means for this purpose, notches one or two thousandths of an inch in depth have been punched in the member 11 at 15 and 16 to accommodate the legs 13a and 14a. Similarly, shallow notches 17 and 18 are formed in the member 12 to hold the legs 13a and 14a from shifting longitudinally. As a further means of preventing such motion the notches 15 and 16 in the member 11 terminate in spurs 19 and 20 which fit into notches cut in the members 13 and 14 respectively.

The other legs 13b and 14b of the C-shaped members 13 and 14 are shorter than the legs 13a and 14a and extend closely toward but do not abut the leg 12 at its ends, forming therewith air gaps G₁ and G₂, respectively, of high magnetic reluctance. The central parts of the members 13 and 14 are designated by the characters 13c and 14c.

When the parts are assembled in their proper relationship, with the various coil sections in place, the core members are placed under heavy pressure, as by an arbor press, and core bands 21 and 22 of steel plate are put into the positions shown, the ends of each band being united as by welding or riveting. To make as tight a fit as possible, wedges 23 and 24 of hard insulating material are inserted between the bands 21 and 22 and the member 11 while the parts are under pressure. The transformer is preferably enclosed in a casing similar to the one shown in Figure 2.

The primary winding coil section P is energized by way of the leads 25 and 26 from a source of alternating current electrical energy 27, such as the standard single phase sixty cycle commercial mains at 110 or 220 volts.

One terminal of the coil S₁ is grounded to the core at 28 and its other terminal is connected by a lead 29 to one terminal of the tube T. Similarly, one terminal of the coil S₂ is grounded to the core at 30 and its other terminal is connected by a lead 31 to the other terminal of the tube T. The grounding of the coils S₁ and S₂ is

such as to place the coils in series where the load is not grounded, but when the mid-point of the load is grounded, the coils may be connected in opposition, that is, so that their output terminals are at the same potential, positive or negative, at the same instant. Where the load mid-point is grounded, a separate circuit is formed for each coil and its half of the load. The transformer core is grounded as at 32.

As the current flowing through the primary winding P changes in magnitude and direction in response to the alternations of voltage impressed across its terminals by the source 27, a magnetic flux of correspondingly varying magnitude and direction is generated in the core member 11 and traverses a complete circuit including the member 11, the long legs 13a and 14a and the member 12 and linking the secondary winding coil sections S₁ and S₂. The path followed by the flux during one half cycle of the applied potential is indicated in the figure by arrows. Due to the constantly changing nature of the flux, a voltage is induced across the terminals of the secondary coil sections S₁ and S₂.

This voltage across the terminals of the coils is also impressed across the tube terminals by way of the leads 29 and 31. When it reaches such a value across the tube T that the gas therein becomes ionized and conductive, a current will flow through the tube and its secondary winding coils S₁ and S₂. The current in the coils S₁ and S₂ will generate counter magnetomotive forces opposing the coursing of the main flux and causing the major portion of that flux to seek a path of less reluctance. Such a path is found from member 11 through the central part 13c, the short leg 13b and its included air gap G₁, member 12, air gap G₂, short leg 14b, and central part 14c back to member 11. By virtue of this shunting of the major portion of the flux around the coils S₁ and S₂ the current in those coils is limited to a safe value. Enough flux continues to link the coils S₁ and S₂ to maintain a steady flow of current through the tube T until the electrical potential from source 27 applied across the primary coil P decreases almost to zero near the end of its half cycle. Upon further decrease in potential in following through the cycle, the tube T becomes extinguished.

When the primary current has alternated to its other half cycle, the tube meanwhile having become extinguished, as the potential across the secondary winding builds up and the tube strikes again the paths of magnetic flux will be the same as those outlined above, except that the flux will course in the opposite direction. Thus, the flux will course through bar 11, central portion 14c, short leg 14b, air gap G₂, bar 12, air gap G₁, short leg 13b, and central part 13c back to bar 11.

In the event the tube T should become short-circuited, as by a film of moisture, matted insect bodies and the like about the terminals, the operation of the transformer will not be impaired but will be similar to the condition existing when the tube is ignited in normal operation. Thus, if tube T is short-circuited, the current beginning to flow in its secondary coils S₁ and S₂, from the beginning of the half cycle of applied potential will commence to develop strong counter magnetomotive forces which will cause the main body of flux to pass around coils S₁ and S₂ from bar 11 through central part 13c, short leg 13b, air gap G₁, bar 12, air gap G₂, short leg 14b and central portion 14c back to bar 11. That portion of the magnetic flux which courses through the

long legs 13a and 14a of core members 13 and 14, thereby interlinking the primary winding and the coils S₁ and S₂, is insufficient to induce such electromotive forces in coils S₁ and S₂, as to cause an excessive flow of current through them. The value of the current flowing under short-circuit conditions is substantially the same as that flowing during the conductive period of the luminescent tube. Neither is sufficient to cause substantial heating and consequent damage to the winding.

Should one of the coil sections, say the coil S₁, become grounded in operation, the tube T will not be operated because the potential of the other coil S₂ will not be sufficient to ionize the gas in the tube. The current flowing in the grounded coil S₁ will not be excessive due to the shunting of the main magnetic flux around the coil. As the current induced in the grounded coil S₁ rises from a zero value in response to the rising of the potential applied across the terminals of the primary winding P, a counter magnetomotive force is generated by the coil S₁, bucking the main flux and causing a major portion of it to course along a path of high reluctance extending outwardly around the coil S₁. This path is from the bar 11 through the central portion 13c, short arm 13b, air gap G₁, bar 12, and long leg 14a back to bar 11, excluding the coil S₁ but including and linking the coil S₂. A similar condition of operation will obtain when it is the coil S₂ which becomes grounded. In that situation, a major portion of the flux will pass through the shunt path including the air gap G₂ and short leg 14b but will continue to link the coil S₁.

On the other hand, when the tube T is open-circuited, as by the breaking of the tube or a substantial increase in the pressure of its gas, there will be no need to divert flux around the secondary coils. There is no current flowing through the coils S₁ and S₂ and accordingly no counter magnetomotive forces are developed therein. Hence with coils S₁ and S₂ in open-circuit condition, the flux continues to course through the long legs 13a and 14a of the members 13 and 14, linking the coils S₁ and S₂. Likewise, when one of the coils, say the coil S₁, is open-circuited, the whole secondary circuit is thereby broken. No counter magnetomotive forces are then developed by the secondary coils and the magnetic flux will course through the core as it does in normal operation when the tube is not ionized.

Where desired the highly beneficial operating characteristics of my transformer apparatus are achieved by modifying the construction of the apparatus as by doubling the number of C-shaped members and secondary coil sections thereon and providing two instead of one long linear member and having the C-shaped members abutting each other in pairs, their long legs being extended to form bar portions on which primary coil sections are mounted.

Thus referring to Figure 2 of the drawings, I have shown a transformer having a core comprising two parallel linear members 35 and 36 and four substantially C-shaped members 37, 38, 39 and 40. The long legs 37a, 38a, 39a, and 40a of the C-shaped members are extended from the back of the C-shapes and are paired in abutting relationship, forming bar portions on which primary coil sections are mounted. Thus one primary coil section P₁ is mounted over the abutting ends of the long legs 37a and 38a and the other primary coil section P₂ is positioned on the bar

formed by the abutting ends of the long legs 39a and 40a. The other ends of the long legs 37a, 38a, 39a and 40a abut the bars 35 and 36, intermediate their ends, in shallow notches 41, 42, 43, and 44, respectively, formed in those bars. Secondary winding coil sections S₁, S₂, S₃ and S₄ are mounted on the inner ends of the long legs 37a, 38a, 39a and 40a, respectively.

The core parts are held in their proper relationship by metal bands 45 and 46, which extend around the bars 35 and 36 and along the lengths of the long legs 37a and 38a in the case of the band 45 and along the long legs 39a and 40a in the case of the band 46. The parts are placed in an arbor press in which they are subjected to a force between ten and forty tons and tight joints are assured by inserting wedges 47, 48, 49 and 50 under the metal bands.

The transformer is preferably enclosed in a casing 51, cushioning pads 52 and 53 of felt or other suitable material being interposed between the core and the casing.

The primary winding coil sections P₁ and P₂ are connected together in series by a lead 54 at their inner terminals. Their outer terminals are connected by leads 55 and 56 to a source of alternating current electrical energy 57 which is similar to the source 27 of Figure 1.

The secondary winding coil sections S₁, S₂, S₃, and S₄ are grounded to the core at 58, 59, 60, and 61, respectively. Their other terminals are connected to the one terminals of luminescent tubes T₁, T₂, T₃, and T₄ by leads 62, 63, 64, and 65, respectively. The other terminals of the tubes are grounded at 66, 67, 68, and 69 respectively. The ground connections 58 and 60 for the coils S₁ and S₃ are preferably those which will place their other terminals, and thus the leads 62 and 64, in corresponding phase relationship. For this reason it is possible to use a single porcelain bushing 70 for both the leads 62 and 64, instead of an individual bushing for each lead, and thus an economy is effected. Another economy is possible in the cable used. The leads 62 and 64, being always at about the same potential, may be parts of a multi-conductor cable, which is cheaper than individual cables for each lead. Similarly, the coils S₂ and S₄ are preferably grounded at their one terminals which will make the leads 63 and 65 from their other terminals be always at potentials of corresponding phase relationship. Accordingly, only one bushing 71 is necessary for both leads 63 and 65, which may be parts of a multi-conductor cable instead of separate cables. The core itself is grounded, as at 72.

The core member 37 has, in addition to the long leg 37a, a short leg 37b and a central portion 37c. The short leg 37b forms with the end of the bar 35 an air gap G₁ of high magnetic reluctance. Similarly, the core members 38, 39, and 40 have short legs 38b, 39b, and 40b and central portions 38c, 39c, and 40c. The short legs 38b, 39b, and 40b form air gaps G₂, G₃ and G₄ with the bars 35 and 36.

In the operation of the transformer illustrated in Figure 2, as the voltage impressed across the terminals of the primary winding coil sections P₁ and P₂ by the source 57, rises from a zero value at the beginning of a half cycle, a current begins to flow in the primary winding. This current generates a flux in the iron core which courses through the core along a path of low reluctance interlinking the primary and secondary windings. The path followed by the flux in one half cycle of the applied potential is illustrated in the figure by

arrows. As the flux changes in magnitude it induces an electromotive force in the secondary coil sections S_1 , S_2 , S_3 , and S_4 . When the voltage across the terminals of one of the secondary coils, say the coil S_1 , reaches such a value that, being impressed across the terminals of the tube T_1 by way of the lead 62 and the ground connections, it ionizes the gas in tube T_1 and thereby renders the tube conductive, a current begins to flow in this tube and the coil. The current will not reach an excessive value because it creates a back magnetomotive force causing a major portion of the main magnetic flux to be by-passed outwardly around the coil from the long leg 37a through the central part 37c, short leg 37b and air gap G_1 to the bar 35. If the other tubes have not yet become ignited, the flux then passes from the bar 35, through the long legs 39a and 40a, the bar 36 and the long leg 38a back to the member 37. Enough flux still continues to link the coil S_1 to maintain a steady flow of current in the tube T_1 until the current in the primary winding P_1-P_2 decreases almost to zero near the end of the half cycle of applied voltage, at which time the tube becomes extinguished. It will be apparent that the flux shunted around the coil S_1 will continue to link the coils S_2 , S_3 , and S_4 and hence that their operation will not be affected.

In like manner, the coils S_2 , S_3 and S_4 will light the tubes T_2 , T_3 and T_4 respectively, when the voltages induced in those coils reach values sufficiently high to ionize the gas in the tubes. The current in any of the secondary circuits will not reach an excessive value because it will generate a back magneto-motive force in the coil section, causing the major portion of the main magnetic flux to be by-passed around the coil section through its associated shunt member 38b, 39b, or 40b and the included air gap G_2 , G_3 or G_4 . The main flux will continue to link the inoperative coil sections at this time. Enough flux will link the operative coil section to maintain a steady flow of current in its tube load until the current in the primary winding approaches a zero value near the end of a half cycle of applied potential.

When, for example, the tubes T_1 and T_3 are ignited at the same time, the other tubes not having become operative as yet, the major portion of the main flux will course along a path including the right hand end of long leg 37a, central part 37c, short leg 37b, air gap G_1 , bar 35, air gap G_3 , short leg 39b, central part 39c, the right hand end of long leg 39a, long leg 40a, bar 36 and long leg 38a back to the member 37. Also, a similar situation is met where the other two coils S_2 and S_4 are operating but the coils S_1 and S_3 are not operating. In that case, the major portion of the main magnetic flux will course along a path of high reluctance passing outwardly around and excluding the coils S_2 and S_4 but linking the coils S_1 and S_3 . Moreover, in any other condition of operation with some coils operative and some inoperative, a major portion of the flux will be by-passed around the operative coils but will continue to link the inoperative ones.

It will be understood that, while I have described the operation of the transformer during one half cycle of the applied electromotive force, the operation will be the same during the other half cycle. The paths followed by the flux will be identical except that the flux will then be coursing in the opposite direction. Where a 60-cycle course of primary current is used, the tubes

will be lighted 120 times a second. Due to persistence of vision the tubes will appear to emit a steady glow of light.

While, as a matter of convenience in describing the operation of my transformer apparatus, the various stages in the operation of the four luminescent tubes T_1 , T_2 , T_3 and T_4 and the possibilities attending this operation are treated separately, each without special regard to the operating of the other, it will be understood that under actual operating conditions all the luminescent tubes are rendered conductive and luminous at about the same instant and at about the same instant become non-conductive and non-luminous. During those brief periods when the tubes are in their non-conductive states, the total magnetic flux courses along the linear core members 35 and 36 and the long leg portions 37a, 38a, 39a and 40a of the C-shaped members 37, 38, 39, and 40 effecting the closure of the magnetic circuit. During those periods when all the tubes T_1 , T_2 , T_3 and T_4 are in their conductive conditions, a major portion of the magnetic flux courses along the longest possible magnetic path which includes the central portions 37c, 38c, 39c and 40c and the short legs 37b, 38b, 39b and 40b of the C-shaped members 37, 38, 39, and 40 and the included air gaps G_1 , G_2 , G_3 and G_4 , the remaining portion of the magnetic flux continuing along the short path of low reluctance and interlinking the primary and secondary windings.

Where one tube becomes grounded in operation, say the tube T_1 , as by the formation of a film of conductive moisture, ice, sleet, matted insect bodies, and the like between the terminals of the tube or between the high potential terminal and ground, an excessive current will not flow through its secondary winding coil section S_1 due to the peculiar magnetic shunt construction provided. As in normal operation when the tube T_1 is ionized and conductive, the current flowing through the coil S_1 under short-circuit conditions will set up a magnetomotive force bucking the main flux. This back magnetomotive force will cause the major portion of the main flux to pass outwardly around the coil S_1 through the magnetic shunt path of high reluctance comprising the central part 37c, the short leg 37b and the included air gap G_1 into the bar 35 and through the members 39, 40, 36 and 38, back to member 37. By virtue of this action, the short-circuit current will be limited to a safe value, ordinarily not exceeding the value of the current which flows under normal operating conditions. It will be apparent that the same protection is afforded when it is the coil section S_1 and not the tube T_1 which becomes grounded.

Similarly, when any one of the other tubes or secondary winding coil sections becomes grounded in operation, the current flowing through the coil section will be limited to a safe value in the manner described above. The major portion of the main flux under such circumstances will be by-passed around the secondary coil through a magnetic shunt path of high reluctance including the short leg of the C-shaped core member on which that coil is mounted and its associated air gap.

Where one of the tubes, say the tube T_1 , becomes open-circuited as by breaking of the tube or a substantial reduction in its vacuum, it will be apparent that no current will flow through the secondary winding coil section S_1 of that tube. The operation of the other tubes will not be affected and the main magnetic flux will con-

tinue to course through the long leg 37a of the C-shaped member 37, linking the coil S₁, as well as the other coils S₂, S₃, and S₄.

Similarly, when any of the other tubes or coil sections becomes open circuited in operation, no current will flow through that coil section although the main flux continues to interlink it with the primary winding. The other coil sections and tubes will continue to operate normally.

It will be understood that my transformer is capable of many modifications within the spirit of my invention. Thus, the secondary coil sections of the transformer shown in Figure 2 may be connected together in series in any combination desired so as to operate a tube requiring twice the voltage of the tubes illustrated. With such a connection, the maximum voltage to ground at no point will exceed the maximum voltage generated by any one coil section, although the voltage across the tube terminals is double that across any one coil section. It is also feasible to connect pairs of coils in opposition to operate a load where that load is grounded approximately at its midpoint.

In the transformer of Figure 2 it may be desired to make the C-shaped members 37 and 38, on the one hand, and the members 39 and 40 on the other hand, of one integral piece. Such a construction would eliminate two butt joints in the core and would therefore reduce the reluctance of the main magnetic path. Where the core is so made, the primary coil sections P₁ and P₂ are wound upon their core members.

Another possible modification of the transformer is one in which the positions of the C-shaped members are reversed, that is, the members are turned around so that the main magnetic path is on the outside of the core and the shunt legs are inside. That construction has the advantage that fringing of the magnetic flux to the transformer casing and consequent loss in efficiency are diminished.

It will be apparent that my transformer is exceedingly compact, there being a minimum of interior space which is not utilized. The space occupied by the windings is all inside the outer confines of the core. Because of the compact arrangement, a minimum of expensive insulating compound is required.

Due to identity of shape of many of the core members the smallest possible number of expensive dies are required in the manufacture of the core. This feature also results in economy of the materials used in the core.

Inasmuch as the output terminals of adjacent coil sections are designed to correspond in phase, only one bushing is required for the two high potential leads from those coil sections. Moreover, since the other terminals of the coil section are grounded, no bushings are required for them. As there is substantially no voltage difference between adjacent high potential leads, multi-conductor cables can be used for them instead of individual cables. Finally, due to the grounding of the one sides of the coil sections, no high tension cable is required for that side of the circuit. The elimination of high potential cables and bushings on the ground sides and the reduction in the number of them required on the other sides of the secondary circuits constitute considerable savings in expense of material and also reduce the labor charges for installation.

The outside shunt construction embodied in my transformer is highly efficient in operation. Flux leakage by way of stray magnetic fields is

reduced to a minimum. There is high coupling of the secondary coils at the start of each half cycle of primary current. The transformer is symmetrical in shape and it is balanced in operation.

Each individual secondary winding coil section of my transformer is protected from overheating in case of its becoming short-circuited to ground by a magnetic shunt associated with 10 that coil section. Accordingly, a minimum of copper is required in the secondary windings, as the wire does not have to be large enough to withstand an excessive flow of current. Where each coil operates an individual load, each coil 15 is independent of the others, so that inoperativeness of one coil due to short or open-circuiting of the coil or its tube load affects only the operation of that tube and does not interfere with the operation of the other tubes.

20 Due to the manner of assembling the transformer core parts, no rivets or bolts being used to bind the laminations together, eddy currents in the core are reduced to a minimum. Therefore, most of the magnetic flux in the core serves 25 a useful purpose and virtually none of it is wasted. Moreover, heating of the core due to eddy currents is substantially eliminated.

Since the core shunt members are integral parts of main core members, changes in the 30 reluctances of the shunt paths due to varying temperature conditions or to stresses set up in long usage are reduced to a minimum.

As many possible embodiments may be made 35 of my invention and as many changes may be made in the embodiments hereinbefore set forth, it will be understood that all matter described herein, or shown in the drawings, is to be interpreted as illustrative and not in a limiting sense.

40 I claim:

1. In electrical transformer apparatus of the character described, in combination, a core including two spaced substantially parallel linear portions and at least a spaced pair of substantial 45 C-shaped portions, said C-shaped portions having one legs extending between the linear members and forming therewith a closed magnetic circuit of low reluctance and other legs forming therewith shunt circuits of high reluctance, secondary windings mounted on said one legs of said C-shaped portions with their one terminals grounded to the core and their other terminals connected to load means, and a primary winding mounted on said core and linked thereby 50 with said secondary windings.

2. In electrical transformer apparatus of the character described, in combination, a primary winding, a plurality of secondary windings each of which comprises one coil section, a core interlinking said primary and secondary windings, said core including a plurality of individual C-shaped portions corresponding in number to said plurality of secondary winding coil sections symmetrically positioned with respect to the remainder of the core and the primary winding mounted thereon on the one legs of said C-shaped portions abutting another portion of the core and forming a short main magnetic circuit of low reluctance said secondary coils being respectively mounted 60 on said legs of said C-shaped portions and the other legs forming parts of shunt paths of high reluctance around each of said secondary winding coil sections, and binding means holding said individual C-shaped portions to the remaining 65 70

portions of said core in said abutting relationship.

3. In electrical transformer apparatus of the character described, in combination, a transformer core comprising two straight parallel portions and two C-shaped portions with their one arms facing and abutting one of said straight portions and with their other arms facing but not abutting said one straight portion and with their backs abutting said other straight portion, forming thereby a closed magnetic circuit and two auxiliary circuits, a primary winding mounted on one of said straight core portions, and a secondary winding comprising two coil sections each of which is mounted on the abutting arms of said C-shaped portions.

4. In electrical transformer apparatus of the character described, in combination, a transformer core comprising two straight parallel portions, and two C-shaped portions abutting therewith at opposite ends thereof with their open sides facing a straight portion, said C-shaped portions each having a fore-shortened leg approaching an abutting relationship with an extreme end of a straight core portion and forming therewith an air gap, whereby there is achieved a closed path for a main magnetic flux and also shunt paths away from parts of the closed path.

5. In electrical transformer apparatus of the character described, in combination, a transformer core comprising two straight parallel portions, and two C-shaped portions each one of which is in abutting relationship with adjacent ends of said parallel portions with the open parts of said C-shaped portions facing one of said parallel portions, said C-shaped portions each having a fore-shortened leg approaching an abutting relationship with an end of one said parallel portion and forming therewith an air gap, whereby there is achieved a short main path for magnetic flux and also two shunt paths around parts of the main path.

6. In electrical transformer apparatus of the character described, in combination, a transformer core comprising two straight parallel pieces having correspondingly inwardly facing recessed sections, two C-shaped pieces facing one of said straight pieces with their one leg portions set within the recessed sections of said piece and their other leg portions being fore-shortened and forming air gaps therewith and with their backs set within the recessed sections of said other straight piece, and binding means maintaining said straight and C-shaped pieces in assembled relationship.

7. In electrical transformer apparatus of the character described, in combination, two linear core members spaced in parallel relationship, two substantially C-shaped core members each having a long leg portion so positioned as to abut the linear core members to effect a closed magnetic circuit of low reluctance and each having a short leg portion so positioned as to form a shunt path of high reluctance to effect a lengthening of the magnetic circuit, a primary winding mounted on one of said linear core members, and two secondary windings each comprising one coil section mounted on a long leg portion of one of said C-shaped members.

8. In electrical transformer apparatus of the character described, in combination, two linear parallel core members, two substantially C-shaped core members spaced apart and cooperatively associated with said first-mentioned core members effecting a closed magnetic circuit therewith by way of their one legs and establishing shunt core paths including air gaps by way of their other legs, a primary winding mounted on one of said linear core members, and two secondary windings mounted on said C-shaped core members, each of said secondary windings consisting of one coil section with its one terminal grounded to said core members and its other terminal connected to an individual negative load.

9. In electrical transformer apparatus of the character described, in combination, two linear core members spaced in parallel relationship; four substantially C-shaped core members each having a long leg portion so positioned as to abut at its one end one of said linear core members intermediate the ends thereof and to abut at its other end another of said C-shaped members to effect a closed magnetic circuit, each of said C-shaped members also having a short leg portion so positioned as to form a shunt path and effect a lengthening of the magnetic circuit; a primary winding comprising two coil sections mounted over the abutting ends of the long leg portions of said C-shaped members; and four secondary windings, each comprising one coil section mounted on a long leg portion of one of said C-shaped members.

10. In electrical apparatus of the character described, a double transformer comprising, in combination a magnetic core, a primary winding consisting of two coil sections positioned on opposite legs of said core, and, two secondary windings positioned on said opposite legs of the core each secondary winding consisting of two coil sections located on opposite sides of one of the primary coil sections and connected together in series, said core including offset portions individually extending outwardly and around separate ones of said secondary winding coil sections to provide paths for magnetic flux which does not link said secondary winding coil sections with said primary winding during closed-circuit operation of the secondary coil sections.

11. In electrical transformer apparatus of the character described, a double transformer core comprising, in combination, two parallel straight core portions, two pairs of abutting interconnecting core portions, each of which pair comprises two core portions abutting each other and each of said abutting core portions having offset arm portions approaching a butt relation with said straight core portions and forming an air gap therewith, whereby there is achieved a short closed main magnetic circuit of low reluctance and a plurality of individual departures from this main magnetic circuit of high reluctance by way of the offset arm portions of said interconnecting core portions and adjacent parts of said straight portions and the air gaps included herewith.

CHARLES PHILIPPE BOUCHER.
